UNITED STATES PATENT OFFICE.

STEPHEN R. KROM, OF PLAINFIELD, NEW JERSEY.

PULVERIZING-MILL.

No. 823,127.

Specification of Letters Patent.

Patented June 12, 1906.

Application filed January 7, 1904. Renewed August 8, 1905. Serial No. 273,321.

To all whom it may concern:

Be it known that I, STEPHEN R. KROM, a citizen of the United States, residing at Plainfield, in the county of Union and State of New Jersey, have invented an Improvement in Pulverizing-Mills, of which the following is a specification.

My invention relates to improvements in roller-mills adapted for pulverizing ores, minerals, cement-klinker, and other friable substances and reducing the same to a fine consistency, with the object of improving and increasing the output.

In carrying out my invention a series of rollers mounted on short freely-pivoted crank-shafts are driven at a high speed, and they run against the hardened inner surface of a ring or annulus, the centrifugal force producing a very heavy crushing pressure, which varies with the speed. The materials to be pulverized are automatically fed and centrally and equally delivered to centrifugal feeders, which deliver the materials in a wide thin stream adjacent to and directly in the path of the rollers, which pass over and pulverize the same before it can fall away.

The rollers and centrifugal feeders are in coacting sets, and the materials are preferably delivered the full width of the rollers.

These devices are preferably arranged in a vertical plane. They are suitably mounted, operated, housed, and oiled, the details of which are hereinafter more particularly described.

In the drawings, Figure 1 is a central vertical section through the apparatus comprising my improvement. Fig. 2 is a plan and partial central section. Fig. 3 is a vertical section through the case and one of the roller devices and a centrifugal feeder and an elevation of the other rollers and feeders. Fig. 4 is an elevation of the base, the housing, and parts associated therewith in the same general position as Fig. 3. Fig. 5 is a section and elevation at about the dotted line $x-x$ of Fig. 2 looking toward the support for the rollers. Fig. 6 is a partial elevation representing a modified position of the rollers with reference to their crank-shaft. Fig. 7 is a partial vertical section and side elevation, and Fig. 8 an elevation and partial section, of the parts shown in Fig. 7, Figs. 7 and 8 representing a

modified construction of the support for the rollers.

Referring especially to Figs. 1, 3, and 4, a represents a cast base with a discharge-throat a^2 in the forward part below the semicircular portion in the base. a' represents a housing, also with a semicircular portion fitting over the semicircular portion of the base and securely connected thereto by the bolts shown in Figs. 3 and 4. Secured to the base and the housing upon the outer left-hand surface of the structure is a central plate g and doors g' hinged thereto and closing up the circular aperture within this portion of the base a and the housing a' . A bearing-box b fits upon and is bolted to the portion of the cast base at the right hand of Figs. 1 and 2, and a cap or cover b' of smaller area is bolted to the bearing-box b , the shaft c passing through the bearing-box and between the same and the cover b' . In this bearing-box b , as shown in Fig. 1, there is an oil-receptacle 2 and apertures formed through the bearing-box into the oil-receptacle and also apertures formed in and through the cap or cover, which in the cap or cover are closed by plugs 4. Around the shaft c , within the apertures of the bearing-box and cover and depending into the oil-receptacle and into any oil contained therein, are chains 3, which revolve with the rotation of the shaft and carry up oil and deliver the same upon the shaft, so that the oil will spread longitudinally of the shaft into the bearings for its proper automatic lubrication.

A pulley c' is secured to the outer end of the shaft c , and power is communicated by any suitable belt from any suitable source of supply to the pulley c' and shaft c . A fly-wheel d is connected to the shaft c at the opposite end from that to which the pulley is secured and at the opposite side of the bearing-box b . This fly-wheel instead of being made with spokes is preferably made with a web d' , in which are formed hubs to receive the crank-shafts n , hereinafter described. This fly-wheel therefore performs the two-fold function of a regulator of the speed and of a support or carrier for the crushing-rollers. A disk e , with a recessed or offset center, surrounds the reduced end c^2 of the shaft c , said disk at the recessed center being secured to the central surface of the fly-wheel d —that

is, the hub thereof—and the disk *e* is provided with elongated openings *e'*, equally spaced apart, (see Fig. 5,) the said disk closing off the circular recess between the base *a* and the housing *a'* at the opposite side thereof from that closed by the central plate *g* and doors *g'*.

f is an annulus or ring, preferably of steel, with a hardened inner face, and the same is received within the circular recess between the base and housing and is securely held in position by forcing the housing *a'* to place upon the base *a* by the bolts shown in Fig. 4, or the same may be held in any other suitable or convenient manner.

Referring especially to Figs. 1 and 2, *h* represents a hopper structure with a forward extension *h'* and a tubular inner prolongation or extension *h''*, the axis of the tubular extension agreeing exactly with a prolongation of the axis of the shaft *c*. This hopper and the parts formed therewith are suitably secured to and supported by the central plate *g*. The lower portion of the extension *h'* is preferably formed hollow and with parts constituting bearings for a shaft *i*, on the outer end of which is a pulley *i'* and on the inner portion of which is a screw conveyer *k*. A disk *5* is side of the bearing from that occupied by the pulley *i*, so as to prevent any accidental longitudinal movement of the shaft *i* and the parts connected therewith. The screw conveyer is in so much of the tubular extension as passes within the central plate *g* and beneath the mouth of the hopper *h*, so that any material delivered into the hopper *h* may be moved along the tubular extension by the rotation of the pulley *i'*, shaft *i*, and screw conveyer *k*, which may be operated by a band or chain from any suitable power device. The inner end of the tubular prolongation *h''* at the lower portion is made with a discharge-aperture *7*. I provide a tubular hub *l*, secured to the reduced end *c'* of the shaft, the tubular part thereof being of sufficiently liberal dimensions to loosely receive the free end of the tubular prolongation *h''* and to freely revolve with the shaft around the same. This tubular hub *l* is made with faces 6, triangularly-disposed with reference to one another, and to these faces flanges on the larger ends of the centrifugal feeders *m* are securely fastened by bolts, as shown in Fig. 3. These centrifugal feeders *m* are tapering and curved in the direction of rotation, the apertures of their delivery ends *m'* being small and of substantially the width of the inner face of the annulus or ring *f*, this width preferably being produced by enlarging the said centrifugal feeders adjacent to the free ends. (See Fig. 3.)

The crushing-rollers are mounted upon crank-pins *n'*, which crank-pins are carried

by the cranks *n'*, and the crank-shafts *n* of 65 said cranks are received in the hubs of the fly-wheel *d*, there being nuts *8* on the ends of the crank-shafts against the opposite surface of the said hubs to that against which the cranks *n'* bear. The cranks, their crank-shafts and crank-pins are thus loosely mounted, so that they are free to swing. Around each crank-pin *n'* is an auxiliary sleeve *9*, and around the back end of the crank-pin is a flanged sleeve *o*. (See especially Fig. 2.) The flanged sleeve *o* is longer than the auxiliary sleeve *9*, and while one end of the auxiliary sleeve *9* comes against the inner end of the flanged sleeve *o* the other end of the auxiliary 80 sleeve *9* abuts against the nut and washer *11* upon the end of the crank-pin, and the projecting portion of the flanged sleeve *o* is terminated with a screw-cap *12*. By this construction there is sufficient bearing for the 85 roller, and the screw-cap *12* covers and prevents the access of dust from the crushing operations to the end of the crank-pin and the auxiliary sleeve, the said flanged sleeve *o* being essentially held to the crank-pin by the 90 presence of the auxiliary sleeve *9*, coming between the same and the nut and washer *11*. In cross-section the outer surface of the flange of the sleeve *o* is inclined to the axis of the crank-pin, and a collar *o'* surrounds the 95 flanged sleeve *o*, and this is made with a surface also inclined to the axis of the crank-pin, but in the opposite direction, and this collar *o* is securely held in place to the flanged sleeve *o* by bolts *10*, which pass through the parts. 100

Each roller structure is completed by a ring or annulus *r*, which extends around the flanged sleeve *o* and collar *o'* and the inner surface of which is provided with inclines in opposite directions to agree with the inclined 105 surfaces of the said flanged sleeve and collar. Consequently when tension is applied to the bolts *10* they act to draw together the collar *o'* and the flanged sleeve *o* and to clamp more firmly to them, and in position, the said ring 110 or annulus *r*. This ring or annulus *r* is made with a hardened-steel surface and is adapted to run against the inner surface of the annulus or ring *f*.

By reference to Fig. 3 and to the arrow 115 thereon, showing the direction, it will be noticed that in the line of motion the crank-pins *n'* are forward of the crank-shafts *n*. Consequently the rollers are pushed ahead, and the centrifugal motion forces the same 120 against the inner surface of the ring *f*, while in Fig. 6 the crank-pin in the line of motion is back of the crank-shaft and the roller is drawn behind the crank-shaft instead of being pushed ahead, as shown in Fig. 3. I do 125 not limit myself in this particular, as the structures are the same and the action in the one is the equivalent of the other.

With the construction Fig. 6 in the particular just described it will be apparent that the rollers will keep their own position and will not require any additional instrumentality to keep them in place; but with the structure shown in Fig. 2, where the rollers are pushed ahead of the crank-shafts, some means is required to maintain the rollers in position. This means is the openings e' in the disk e , (see Fig. 5,) these openings receiving the rear end of the flanged sleeve o and in diameter in one direction being slightly greater than the diameter of the sleeve o , but in a direction at right angles thereto being appreciably elongated, so as to provide for a movement of the roller toward the ring f and for any wear of the surface of the roller and the ring f , it being possible with the disk e and the openings e' to move toward the ring f , but not appreciably away from the same.

In the modified structure shown in Figs. 7 and 8 the fly-wheel d is provided with radially-disposed recesses 13, the edges of which are overlapped by plates 14, secured to the fly-wheel. Heads s are received and slide in these recesses beneath the overlapping edges of the plates 14. To each head s there is formed a shaft s' , carrying a roller r' , the shaft s' preferably passing through such a recess as e' in the disk e for limiting its movement, the said recess being arranged radially.

In the operation of the structure hereinbefore described the material to be pulverized is fed into the hopper h . It is moved along in the tubular prolongation h^2 by the screw conveyer k , and it finds an exit at the discharge-aperture 7 of the tubular prolongation h^2 . From this aperture it falls directly against the inner surface of the tubular head l and into the hollow centrifugal feeders m . By the centrifugal motion produced by the high speed of rotation the material is forced along through the centrifugal feeders m regardless of their position, and the material finds an exit at the narrow and wide mouths of the delivery ends of said feeders and against the inner surface of the ring or annulus f slightly in advance of the rollers and directly in their path, so that in the operation this material is practically no sooner delivered than the rollers pass over it and crush it, the materials being pulverized by the weight and centrifugal force applied to the rollers, and the motion of rotation is so quick that it is possible for several rollers to pass over the same particles of material to thoroughly pulverize the same before said particles can fall away from the surface of the ring or annulus f . The material as pulverized falls into the lower portion of the receptacle between the base and the housing and finds an exit through the discharge-throat a^2 . The hinged doors g' are provided for giving access to the receptacle formed between the base and the

housing and to the parts of the rollers and 65 centrifugal feeders for the purpose of cleansing, oiling, and repairing.

I claim as my invention—

1. In a pulverizing-mill, the combination with a ring or annulus against the inner surface of which material is pulverized, of a series of, pivotally-mounted crushing-rollers running on said surface, hollow centrifugal feeding devices in the same plane as the crushing-rollers for delivering the material 70 in front of and into the path of the rollers, and means for feeding the material to be pulverized axially and centrally to and in the same plane as the centrifugal feeding devices. 75

2. In a pulverizing-mill, the combination with a ring or annulus against the inner surface of which material is pulverized, of a series of pivotally-mounted crushing-rollers running on the said surface, a hopper and a screw conveyer centrally placed and adapted 80 for feeding the material to be pulverized to the axial center of the machine, and centrifugal feeding devices receiving the material from the said conveyer and for delivering the same in front of and into the path of the 85 roller. 90

3. In a pulverizing-mill, the combination with a ring or annulus against the inner surface of which material is pulverized, of a series of pivotally-mounted crushing-rollers 95 running on the said surface, means for centrally feeding the material to be pulverized, a tubular portion in the axial center of the machine and surrounding a portion of the central feeding devices, and centrifugal feeders connected to the said tubular structure 100 and revolving therewith and receiving the material from said feeding devices and delivering the same in front of and into the path of the rollers to be pulverized. 105

4. In a pulverizing-mill, the combination with a ring or annulus against the inner surface of which material is forced, of a main central shaft, a series of pivotally-mounted crushing-rollers running on the surface of 110 said ring or annulus, a device connected to the shaft and forming the support for the rollers, a hopper and means axially in line with said shaft for feeding the material to be pulverized, and centrifugal feeding devices 115 also supported upon said shaft and actuated thereby, receiving the material and for delivering the same in front of and into the path of the rollers. 120

5. In a pulverizing-mill, the combination with a ring or annulus against the inner surface of which material is pulverized, of a main central shaft, a series of pivotally-mounted crushing-rollers running on the surface of 125 said ring or annulus, a device connected to the shaft and forming the support for the rollers, a hopper, a tubular prolongation of said hopper axially in line with said shaft, a

5 screw conveyer within said tubular prolongation for feeding the material from the hopper, said prolongation having a discharge-aperture, means for rotating the said conveyer and centrifugal feeding devices receiving the material from said discharge-aperture and delivering the same in front of and into the path of the rollers.

6. In a pulverizing-mill, the combination 10 with a ring or annulus against the inner surface of which material is pulverized, of a main central shaft, a series of pivotally-mounted crushing-rollers running on the surface of said ring or annulus, a device connected to the shaft and forming the support for the rollers, a tubular hub structure connected to and rotating with the said shaft and the series of crushing-rollers, and centrifugal feeders mounted upon said tubular hub and having delivery ends running closely adjacent to the inner surface of the aforesaid ring or annulus and each centrifugal feeder comprising a curved and tapering structure where the curve is in the direction of rotation and means for centrally feeding the material to be pulverized and for delivering the same to the centrifugal feeders.

7. In a pulverizing-mill, and in combination, 30 a main central shaft, a tubular hub structure connected to and rotating with the said shaft, centrifugal feeding devices mounted upon said tubular hub and having narrow delivery ends, each centrifugal feeder comprising a curved and tapering structure 35 where the curve is in the direction of rotation, a tubular part placed axially with said shaft and entering the tubular hub structure and having a discharge-aperture at its inner end, means for holding the material to be 40 fed, and means for feeding the same to the said centrifugal feeders through said tubular part.

8. In a pulverizing-mill and in combination, 45 a main central shaft, a tubular hub structure connected to and rotating with the said shaft, centrifugal feeding devices mounted upon said tubular hub and having narrow delivery ends, each centrifugal feeder comprising a curved and tapering structure 50 where the curve is in the direction of rotation, a hopper, a tubular inner prolongation of said hopper having a discharge-aperture at its inner end, the said tubular prolongation being axially in line with the said shaft and 55 passing into the said tubular hub, a screw conveyer in said tubular prolongation, a shaft upon which the same is mounted, and means for rotating said shaft and screw conveyer, whereby the contents of the hopper 60 are pulverized and are continuously and progressively fed and delivered at the discharge-aperture to the centrifugal feeders.

9. In a pulverizing-mill, the combination 65 with a ring or annulus against the inner sur-

face of which material is pulverized, of a main central shaft and a series of pivotally-mounted crushing-rollers running on the surface of said ring or annulus, a revoluble device mounted upon said shaft and simultaneously forming a fly-wheel and a support for the said 70 rollers, and provided with spaced-apart perforations, crank-shafts passing freely through said perforations and secured to the said revoluble device, cranks formed with said crank-shafts and crank-pins formed with the cranks 75 and upon which the crushing-rollers are mounted.

10. In a pulverizing-mill, the combination 80 with a ring or annulus against the inner surface of which material is pulverized and a main central shaft and supports therefor, of a revoluble device connected to said shaft and performing the office of a fly-wheel and provided with spaced-apart perforations, a series 85 of connected crank-shafts, cranks and crank-pins, the crank-shafts passing through said perforations adapted to swing therein and secured to the revoluble device, a series of crushing-rollers mounted upon the crank-pins, a disk forming the back of the pulverizing-mill housing and provided with spaced-apart elongated perforations receiving the crank-pins and adjacent portions of the crushing-rollers and serving to limit the swinging 90 movement of said crushing-rollers.

11. In a crushing-mill, and in combination, 95 a base and housing forming a substantially vertical casing, a circular device having a crushing-surface within the same, a substantially horizontal shaft projecting into said 100 casing, a revoluble device fixed to and movable with said shaft, a plurality of cranks and crank-shafts carried thereby, and crank-pins formed therewith and projecting into the casing, a roller on each crank-pin located within 105 the casing and by centrifugal force running against the crushing-surface, a fixed structure at one side of said casing, and a revoluble structure at the other side of said casing 110 and mounted on said shaft and together closing the same, at opposite sides centrifugal feeding devices, with their discharge-openings near the crushing-surface and in front of the rollers, a hollow structure forming a support for the centrifugal feeders and mounted 115 on said shaft, and means connected to and passing through the fixed structure at one side of the casing for conveying the material to be crushed to the centrifugal feeders.

12. In a pulverizing-mill, the combination 120 with a shaft, a revoluble device, a series of roller devices mounted thereon and a fixed ring having a crushing-surface against which the rollers bear, of a tubular hub structure mounted on said shaft and having triangularly-arranged faces and perforations, a series of curved tapering hollow centrifugal feeders secured upon the triangularly-ar-

ranged faces of the tubular hub and curved rearwardly or in the direction of rotation, the discharge-apertures thereof coming adjacent to the crushing-surface and in front of the 5 path of the rollers, and means for delivering the material to be pulverized within the said tubular hub to the centrifugal feeders.

13. In a pulverizing-mill, the combination with a shaft and a revoluble part, of a crank-shaft, a crank and crank-pin connected together and pivotally mounted on the revoluble part, a nut and washer on the free end of the crank-pin, an auxiliary sleeve surrounding the major portion of the crank-pin and coming against the washer and nut at one end, a flanged sleeve surrounding said auxiliary sleeve and the crank-pin at one end and extending forward of the crank-pin, a screw-cap closing the end of the same and serving to 20 keep dust away from the contacting surfaces adjacent to the crank-pin, the flange of the flanged sleeve having an inclined surface, a collar surrounding the flanged sleeve and having an inclined surface in the opposite direction, 25 a ring or annulus surrounding the flanged sleeve and the collar and having inner surfaces agreeing with the inclined surface thereof, and bolts passing through the flange of the sleeve and the collar for holding the 30 parts together and for securely clamping the ring or annulus thereto.

14. In a pulverizing-mill, the combination with a shaft and a revoluble part, of a crank-shaft, a crank and crank-pin connected together and pivotally mounted on the revoluble part, a nut and washer on the free end of the crank-pin, an auxiliary sleeve surrounding the major portion of the crank-pin and coming against the washer and nut at one end, 40 a flanged sleeve surrounding said auxiliary sleeve and the crank-pin at one end, and a ring or annulus having a hardened surface mounted upon said flanged sleeve, the parts together forming a roller structure and a device closing the end of the auxiliary sleeve and by which access is had to the nut.

15. In a crushing-mill and in combination, a base and housing forming a substantially vertical casing, a circular device within the 50 same having a crushing-surface, a substantially horizontal shaft projecting into said casing, and a bearing therefor, a central plate and doors hinged thereto and at either side thereof for closing off the housing at one 55 side, and a disk fitting the housing at the opposite side, and means for connecting the same to the said shaft whereby the housing is completely inclosed.

16. In a crushing-mill and in combination, 60 a main central shaft, a series of pivotally-mounted crushing-rollers, a common support for the said crushing-rollers mounted upon said shaft, a disk supported by the said central shaft forming a closure at one

side of the pulverizing-mill and having apertures receiving and within which parts of the crushing-rollers move and are limited.

17. In a pulverizing-mill, the combination with a ring or annulus against the inner surface of which material is pulverized and a 70 main central shaft and supports therefor, of a revoluble device connected to said shaft and performing the office of a fly-wheel and provided with spaced-apart perforations, a series of connected crank-shafts, cranks and 75 crank-pins, the crank-shafts passing through said perforations adapted to swing therein and secured to the revoluble device, and a series of crushing-rollers mounted upon the crank-pins and adapted to run upon the surface of the ring or annulus.

18. In a pulverizing-mill, the combination with a shaft, a revoluble device, a series of roller devices mounted thereon, and a fixed ring having a crushing-surface against which 85 the rollers bear, of a tubular hub structure mounted on said shaft and having triangularly-arranged faces and perforations, a series of curved tapering hollow centrifugal feeders secured upon the triangularly-arranged faces of the tubular hub and curved rearwardly or in the direction of rotation, the discharge-apertures thereof coming adjacent to the crushing-surface and in front of the path of the rollers, a hopper, means for supporting the same, the forward extension of the hopper forming a bearing, a tubular inner prolongation of the hopper communicating therewith, the free end of which passes into the aforesaid tubular hub and is provided with an aperture, a screw conveyer and a shaft therefor within the tubular prolongation of the hopper, and means for rotating the same, for progressing the material to 90 be pulverized and delivering the same 95 through the aperture to the hollow centrifugal feeders.

19. In a pulverizing-mill, the combination with a shaft, a revoluble part, a crank-shaft and crank-pin connected together and pivotally mounted on the revoluble part, of a flanged sleeve in part surrounding the crank-pin and having an internal shoulder, an auxiliary sleeve surrounding the major portion of the crank-pin from the free end to the shoulder of the flanged sleeve, and a nut device on the free end of the crank-pin for retaining the auxiliary sleeve and flanged sleeve in position.

20. In a pulverizing-mill, the combination with a shaft, a revoluble part, a crank-shaft and crank-pin connected together and pivotally mounted on the revoluble part, of a flanged sleeve in part surrounding the crank-pin and having an internal shoulder, an auxiliary sleeve surrounding the major portion of the crank-pin from the free end to the shoulder of the flanged sleeve, and a nut de- 125

vice on the free end of the crank-pin for retaining the auxiliary sleeve and flanged sleeve in position, the flanged sleeve extending beyond the crank-pin, a screw-cap closing the end of said flanged sleeve, a collar surrounding the said flanged sleeve, a ring or annulus surrounding the flanged sleeve and collar, and means, substantially as specified

for connecting and holding said parts together.

Signed by me this 5th day of January, 1904.

STEPHEN R. KROM.
